UNITED STATES PATENT OFFICE.

LELAND L. SUMMERS, OF CHICAGO, ILLINOIS.

PROCESS FOR FORMING NITROGEN COMPOUNDS.

1,242,264.

Specification of Letters Patent.

Patented Oct. 9, 1917.

Application filed April 22, 1914. Serial No. 333,769.

To all whom it may concern:

Be it known that I, LELAND L. SUMMERS, a citizen of the United States, residing at Chicago, in the county of Cook and State of Illinois, have invented a certain new and useful Improvement in Processes for Forming Nitrogen Compounds, of which the following is a specification.

The object of my invention is to provide a process for preparing or forming nitrogenous compounds such as ammonia, (NH_3), nitric oxid (NO), cyanogen (C_2N_2), and various carbonic and other compounds or salts derived from these compounds.

My process in its broader aspect consists in preparing nitrogenous compounds from the nitrogen of the air or other gaseous sources by the use of the element manganese or its compounds. A compound containing manganese such as the common dioxid of manganese, "pyrolusite," is suitably heated in the presence of carbonaceous matter to form various carbids of manganese. While this reaction is in progress, nitrogen from the atmosphere or other sources is caused to come in intimate contact with the heated materials and a reaction takes place causing various compounds of nitrogen, carbon, oxygen and manganese to be formed which may be readily recovered as such or as other compounds containing combined nitrogen in an available form. In the practice of my process various forms of apparatus may be utilized but that illustrated in the accompanying drawings, described in the following specification is particularly adapted for the purpose. It will therefore be understood that the specific disclosure of the apparatus and process herein contained, while representing the form of the invention preferred by me is presented for the purpose of exemplification only and that the scope of the invention is to be derived from the following claims in which I have endeavored to distinguish it from the prior art so far as known to me without, however, relinquishing or abandoning any portion or feature thereof.

In the drawing I have shown a vertical central cross section of the preferred form of the apparatus referred to above. It comprises a stationary element, a rotary element coöperating therewith, there being an annular passage between the two elements through which the material treated passes, together with electrodes for passing a heat-

ing current through the material and twyers for supplying the necessary gases for carrying out the process to the material to be treated. The stationary element of the furnace comprises a base 1 which is preferably formed of cast iron though other refractory material may be employed. A central boss or cone 2 is or may be formed integral with the base which latter likewise comprises an outer annular wall 3, the upper edge of which is channeled as at 4 for a purpose to be presently described. The revoluble member of the furnace comprises an open cylindrical water jacket 6 preferably of cast iron, which is revolvably supported by rollers 7 running within the groove or track 4 referred to above, upon the wall of the stationary member of the furnace. The water jacket 6 is offset inwardly as at 8 and extends downwardly within the walls 3 of the stationary member forming with the stationary cone an annular passage for the material being treated, the walls of which are lined as at 10, 11, with hard metal which may or may not be roughened, for the purpose of grinding and disintegrating the material received in said passage. Above the offset the water jacket is provided with a fire-brick or other suitable lining 11' and the construction is closed at the top by a cover plate 12 having hoppers 13 for feeding material to the interior of the furnace arranged about the axis thereof. Each hopper is provided with a bell 14 which is automatically alternately lowered to permit the material to be treated to enter the furnace and raised to close the discharge opening of the hopper so that the material is discharged a little at a time but continuously during the operation of the furnace. For this purpose each bell 14 is connected by a rod 15 with a lever 16 pivoted at 17 to the upper edge of the hopper and extending beyond the furnace to engage the corrugated or serrated upper edge 18 of an annulus 19 concentric with the furnace and supported by a circular I-beam 20 and transverse beams 21 which may be supported in any suitable manner from the walls of the building in which the furnace is located. Springs 22 tend to maintain the bells in their closed position but as the revoluble member of the furnace revolves the outer ends of the levers 16 travel along the corrugations or serrations of the annular track 18 whereby they are alternately raised against the tension of

the springs 22 to lower the bells and released to permit the springs to raise the bells. A flue 23 opens through the cover plate 12 and furnishes an exit for the gases and volatile products from the operation of the furnace and may connect with a condenser or other suitable means for collecting such volatile products. An annular worm gear or rack 24 surrounds the movable element 10 of the furnace and is engaged by a worm 25 which may be turned by hand wheel 26 or power driven mechanism as preferred to slowly rotate the furnace. The upper end 27 of the cone is preferably made of fire brick or similar refractory material which covers a circular electrode 34 of carbon or other suitable conducting material which is supported upon a plate or disk 29 of insulating material. An insulating sleeve 30 extends through the electrode at its center and the parts are maintained in position by a central bolt 31. A bus-bar or conductor 32 extends axially through the cone, is branched at its upper end and connected to said electrode. The cone has an axial chamber, as shown in the drawing, through which said conductor extends, and a plug 33 of mica or other suitable insulating material spaces the conductor from the adjacent walls of said chamber at the lower end thereof. An annular water chamber 2^a is formed within the central cone and supplied with water through the connections 2^b. The rotary member of the furnace is provided with an annular plate electrode 34' of carbon or other similar material located in the same plane as the electrode 28 and conductors or bus-bars 35 connect the same with the generator which supplies the furnace with electric energy. Twyters 36 supplied by pipes 36 open into the annular passage about the central cone below the electrodes and serve to furnish air or other gas to the material being treated at this level. By reason of the shape of the interior cone and the interior wall of the revolute member of the furnace the passage for the material being treated between said elements gradually converges to a level below the electrodes and 45 twyters and then diverges slightly and openings 37 are formed through the stationary member of the furnace and through the supporting plate 38 therefor through which the material being treated may escape. Plate 38 is supported upon standards 39 and tracks 40 are preferably provided so that a car 41 may be run beneath the furnace and the material being treated be allowed to fall into the same, an annular funnel 42 being 50 provided to direct the latter.

The material being treated is maintained in the furnace to a level above that of the electrodes, and having a considerable resistance, as it passes said electrodes, is 55 highly heated by the current passing there-

through. The heating action is assisted when air or other oxidizing agent is introduced through the twyters by the combustion of the carbonaceous material forming a part of the charge. As it drops below the twyters, however, it is rapidly cooled and ground by the water-cooled grinding plates or facings 9, 10 and ultimately reaches the discharge openings 37 in a finely divided condition.

The operation of the process and apparatus is as follows: Manganese dioxide mixed with an excess of powdered coal or coke is placed in the furnace to a depth covering the electrodes, the hoppers 13 are also filled, the current is turned on, and as both the coke and manganese dioxide are conductors, the material is quickly heated to a bright red heat. The twyters 16 are then opened and preheated air is allowed to enter the furnace causing an intense combustion below the electrodes. The temperature is then adjusted by controlling the current so that the material will have a temperature of from 1000° to 1500° C. depending on the materials used and conditions of operation. As the manganese dioxide is heated in the presence of carbon, the tendency is to reduce the former to a metallic condition but owing to the excess of carbon present, the resulting reaction is the formation of a carbide of manganese which, like all metal carbids having a lower melting point than the metal itself readily fuses under the temperature used. Manganese forms a number of distinct compounds with carbon, all being known as carbids, and represented by the formulas Mn_3C , MnC , MnC_2 , etc. Upon further heating these carbids the manganese is vaporized and the carbon is precipitated as graphite. When atmospheric nitrogen is brought into contact with the highly heated mixture of carbon and manganese, there are formed various nitrides of manganese, the vapor of nascent manganese released from the carbids also reforming higher carbids. The exact reactions at these temperatures are very complex and uncertain, and the above reactions are further complicated by the fact that the carbids and the carbon thereof unite with the nitrogen to form various compounds of cyanogen. These in turn unite with the manganese and with various impurities in the coke and associated with the manganese ore or dioxide. The final products of the reactions are various volatile compounds of manganese, nitrogen, carbon, etc., which are led off by means of the outlet pipe 23, the gases rising from the furnace being conveyed from this outlet to suitable condensers where the nitrides are decomposed to ammonia NH_3 and the cyanids may be either recovered as such and further refined or may be decomposed to form am-

monia. In practice the compounds distilled are obtained in the form of both cyanogen compounds and ammonia, as well as compounds resulting from nitric oxide, NO.

5 The advantages of manganese as the metal employed in the process above described are numerous. The ease with which manganese carbids are formed makes it possible to use lower temperatures than is possible with the alkali or alkaline earth metals, and further manganese has a distinct advantage in readily forming nitrides, carbids, and cyanogen compounds. The metal also exerts a pronounced catalytic effect on nitrogen. In general these reactions start at 1000° to 1100° C. and at 1300° to 1400° C. volatile products carrying combined nitrogen are readily distilled. The exact nature of these products is difficult 10 to determine but in general they are compounds of manganese, carbon and nitrogen, while the gas from the fuel is largely carbon monoxide and nitrogen, the oxygen of the air and the oxygen of the oxides both 15 uniting with the excess of carbon which is present. When coal is used or producer gas is blown in through the twyters 36', the hydrogen present acts to form derivations 20 of hydrocyanic acid.

25 By the use of preheated air in the twyters 36', it is possible to produce a temperature capable of combining the other elements named with the atmospheric nitrogen without the electric resistance furnace, but the 30 products of combustion are then excessive and the presence of the large amount of CO and CO₂ in the furnace gases, causes an excessive oxidizing reaction to take place, tending to deposit the volatile manganese 35 compounds within the furnace through the inter-reaction of the gases, as the volatile mangano-nitrogen compounds are very susceptible to oxidizing influences, manganese having such an affinity for oxygen that it is 40 capable of decomposing water even at ordinary temperatures. Any oxidizing of these volatile compounds deposits carbon and manganese compounds and releases inert nitrogen. In practice therefore the heat by 45 which the required temperatures are attained is partially provided by the electric resistance and partially by combustion, an excess of carbon being continually supplied to the furnace. As the products passing below the electrodes are mostly carbon, the 50 twyters are adapted to supply oxygen to consume this excess of carbon. The residue material passing downward to the grinding linings 10 and 11, is there broken up fine 55 enough to be removed from the furnace when the shell rotates, these products consisting of carbon and impurities which cannot readily be "slagged" and must therefore be removed from the furnace by crushing.

60 65 It will be apparent that either the shell or

the central portion of the furnace can be rotated to accomplish this crushing. I have shown the shell rotating as it thereby forms a positive feeding device and a definite height of material can be more readily and uniformly maintained in the furnace which facilitates the proper distribution of the material and insures a distribution of the nitrogen throughout the mass. It also prevents the escape of air through channels and permits the adjustment of the temperatures for the maximum yields, but I do not confine myself to this arrangement. The type of furnace shown permits the maximum use of the products of combustion and likewise subjects all parts of the charge to a uniform temperature as all portions of the charge are forced to pass between the electrodes and are thereby uniformly heated. The charge is also uniformly subjected to the action of the twyters for the removal of part of the excess carbon and the residue is finally ground fine enough for removal. It will be evident that this automatic regulation and uniform treatment may likewise be utilized for other purposes than the preparation of nitrogenous compounds or for the preparation of compounds of nitrogen by other than manganese compounds, such as nitrides, carbids, cyanids, etc.

95 In actual operation the furnace may be revolved slowly and continuously or it may be operated only at intervals as the removal of refuse and the feeding of material requires. In practice this is determined by the conditions of operation and whether the volatile products are affected by the incoming oxidized products. By reducing and controlling the amount of carbon fed to the furnace and removing the products before the volatile combinations with the nitrogen are formed or distilled or by controlling and limiting the access of nitrogen and carbon monoxide which are largely instrumental in producing the volatile compounds as nitro-carbonyl compounds, the furnace may be used for carbid or nitrid manufacture. When carbid of manganese is one of the products it may be used for the production of methane for gas enrichment. 100 The outlet gases from the pipe 23 contain combustible gases and these may be used as producer gas.

110 I claim:

1. The process of forming nitrogenous 120 compounds and the like, comprising heating manganese-containing material with carbonaceous material in the presence of nitrogenous material.

125 2. The process of producing nitrogenous materials and the like, which consists in heating manganiferous material in the presence of carbonaceous material and a gas containing nitrogen.

3. The process of producing nitrogenous 130

material which consists in heating a mixture of manganiferous and carbonaceous material and passing nitrogenous gases therethrough.

5. The process of forming nitrogenous volatile compounds, which consists in heating a mixture of manganiferous and carbonaceous material and forcing nitrogen-containing gas therethrough.

10. 5. The process of forming volatile nitrogenous compounds consisting in heating a mixture of manganiferous and carbonaceous material, passing nitrogen-containing gases therethrough, drawing off the volatile product and condensing the latter.

6. The process of producing nitrogenous compounds which consists in forming a mixture of manganiferous and carbonaceous materials, passing a heating electric current therethrough and injecting nitrogen-containing gases thereinto.

20. 7. The process of producing nitrogenous

compounds, which consists in forming a mixture of manganese oxid and carbonaceous material and passing nitrogen-containing gases therethrough.

8. The process of producing nitrogenous compounds which consists in forming a mixture of manganese oxid and carbonaceous material, passing a heating electric current therethrough and injecting nitrogen-containing gases thereinto.

9. The process of forming volatile nitrogenous compounds, which consists in mixing manganiferous and carbonaceous materials, passing them continuously between electrodes supplying heating current and injecting a mixture of oxygen and nitrogen into said mixture beneath said electrodes.
